C. F. ASH, JR.

WRENCH

Filed July 18, 1927

INVENTOR.

CHARLES F. ASH, JR.,

BY B. P. Fahlen

"ATTORNEY.

UNITED STATES PATENT OFFICE.

CHARLES F. ASH, JR., OF VALLEY STATION, KENTUCKY.

WRENCH.

Application filed July 18, 1927. Serial No. 206,602.

My invention relates to pipe wrenches.

An important object of the invention is to provide a pipe wrench of the adjustable jaw type, having means whereby it will 5 function like a chain wrench.

A further object of the invention is to provide a wrench of the above mentioned character which is strong, durable and reliable in operation.

10 Other objects and advantages of the invention will be apparent during the course of the following description.

In the accompanying drawings, forming a part of this specification, and in which like 15 numerals are employed to designate like parts throughout the same,

Figure 1 is a side elevation of a wrench embodying my invention,

Figure 2 is a plan view of the same,

20 Figure 3 is a horizontal section taken on line 3—3 of Figure 1,

Figure 4 is an enlarged vertical longitudinal section through the wrench, taken on line 4—4 of Figure 2,

25 Figure 5 is a transverse section taken on line 5—5 of Figure 1,

Figure 6 is a perspective view of the lower jaw element,

30 Figure 7 is a detailed section through the links included in the lower jaw element,

Figure 8 is a plan view of the links included in the upper jaw element,

Figure 9 is a bottom plan view of the links included in the lower jaw element.

35 In the drawings, wherein for the purpose of illustration is shown a preferred embodiment of my invention, the numeral 15 designates a shank, polygonal in cross section having a stationary jaw head 17 rigidly secured

40 thereto. This jaw head is channel shaped in cross section, providing a chamber 18, having a curved bottom wall 19.

The numeral 20 designates an adjustable jaw head, integral with a sleeve 21, slideable 45 upon the shank 15. The shank has a screw-threaded portion 22, engaged by a nut 23, operating through opening 24 in the sleeve 21. The adjustable jaw is moved longitudinally upon the shank by turning the nut 23, as is 50 obvious.

The numerals 25 and 26 designate chain 55 jaw elements. Each of these chains embody a plurality of links 27, having interfitting knuckles 28 and 29, pivotally connected by pins 30. The links 27 in the chain 25 have inwardly projecting ratchet teeth 31, which

face toward the shank 15, while the links 27 in the chain 26 have ratchet teeth 32, facing away from the shank 15. The links 27 in each chain 25 and 26 have extensions 33, to engage 60 within notches or recesses 34, formed in the adjacent link. The function of these extensions and recesses is to limit the inward movement of the links of the chains, beyond a 65 straight line position.

The outermost link 27 of the chain 25 has its knuckle, at the outer end thereof, arranged between a pair of links 35, and pivoted thereto at 36. The links 35 extend into the jaw head 17 and are pivoted therein by a 70 transverse pin 37. The innermost link 27 of the chain 25 is pivoted to the inner portion of the jaw head 17 by a pin 38. The stiff spring 39, has one end thereof rigidly attached to the innermost link of the chain 25, and its opposite end engages the bottom wall 19 of the jaw head 27. This spring 39 constitutes resilient means to move the chain 25 inwardly from the stationary jaw.

75 The adjustable jaw head 20 receives a 80 longitudinally curved carrier 40, which is channel shaped in cross section, and has a longitudinally curved bottom wall 41, and held in place by a pin 41'. Pivoted to the outer end of the outermost link 27 of the 85 chain 26 by means of a pin 42 are links 43, the opposite ends of which are pivoted to the carrier 40 as shown at 44. The innermost link 27 of the chain 26 is pivotally connected with the inner end of the carrier by 90 means of a pin 45. A spring 46 is rigidly attached to the end of this link and engages the bottom wall 41 of the carrier. This 95 spring 46 constitutes resilient means to move the chain 26 inwardly from the movable jaw.

The operation of the wrench is as follows:

The jaws are applied to the work, so that the chains 25 and 26 engage therewith. The nut 24 is adjusted to bring the chains in 100 clamping engagement with the work. The chains 25 and 26 flex inwardly, the chain 25 having its links brought into engagement with or adjacent to the bottom wall 19, while the chain 26 has its links engaging with or 105 brought adjacent to the bottom wall 41 of the carrier 40. These chains flex by virtue of their pivotal connection with the swinging links 35 and 43, and conform to the curvature of the pipe. Upon the active 110 turning movement of the wrench, the chains clamp against the curved walls of their sup-

ports and therefore have clamping engagement with the pipe. When the wrench is turned in a reverse direction the chains free the pipe to permit of such turning movement.

It is to be understood that the form of my invention, herewith shown and described, is to be taken as a preferred example of the same, and that various changes in the shape, 10 size and arrangement of parts may be resorted to without departing from the spirit of my invention, or the scope of the subjoined claims.

Having thus described my invention, I 15 claim:

1. In a wrench of the character described, a shank, a relatively stationary jaw head carried thereby, a movable jaw head mounted upon the shank, a chain element arranged 20 adjacent to the stationary jaw head and having its inner end pivotally connected therewith, links pivotally connecting the outer end of the chain element with the stationary jaw head, a second chain element arranged 25 adjacent to the movable jaw head and having its inner end pivotally connected therewith, and links pivotally connecting the outer end of the second named chain element with the movable jaw head.

2. In a wrench of the character described, a shank, a relatively stationary jaw head carried thereby, a movable jaw head mounted upon the shank, a chain element arranged 30 inwardly of and adjacent to the stationary jaw head and adapted to engage therewith upon being flexed, means pivotally connecting the inner end of the chain element with the stationary jaw head, a link construction pivotally connecting the outer end of the 35 link element with the stationary jaw head, resilient means to move the chain element inwardly from the jaw head, a second chain element arranged inwardly of and adjacent

to the movable jaw head and adapted to engage therewith upon being flexed outwardly 45 and having its inner end pivotally connected with the movable jaw head, a link construction pivotally connecting the outer end of the second chain element and the movable jaw head, and resilient means to move the second named link element inwardly from the movable jaw element. 50

3. In a wrench of the character described, a shank, a relatively stationary jaw head carried thereby, a movable jaw head mounted upon the shank, a chain element arranged inwardly of and adjacent to the stationary jaw head and adapted to engage therewith upon being flexed outwardly, said chain element embodying pivoted links having stop means to limit their inward flexing movement, means pivotally connecting the innermost link of the chain element with the stationary jaw head, a spring attached to the innermost link and engaging the jaw head 60 and adapted to turn the same upon its pivot, a link construction pivotally connecting the outermost link of the chain element and stationary jaw head, and working engaging means carried by the movable jaw head. 65

4. In a wrench of the character described, a shank, a relatively stationary jaw head carried thereby, a movable jaw head carried by the shank, a flexible chain element extending longitudinally of the stationary jaw head 75 and having its ends attached to the stationary jaw head, and a separate flexible chain element extending longitudinally of the movable jaw head and having its ends attached to said movable jaw head, the arrangement being such that the separate chain elements may be flexed outwardly with relation to the jaw heads. 80

In testimony whereof I affix my signature.

CHARLES F. ASH, JR.
